[57] CLAIM

The ornamental design for a shelf unit, as shown and described.

DESCRIPTION

FIG. 1 is a perspective view of a shelf unit showing my new design;

FIG. 2 is a front elevational view thereof;

FIG. 3 is a front right side elevational view thereof;

FIG. 4 is a rear right side elevational view thereof, the rear left side being flat and unornamented;

FIG. 5 is a top plan view thereof;

FIG. 6 is a perspective view of a second embodiment of the shelf unit shown in FIG. 1;

FIG. 7 is a front elevational view thereof;

FIG. 8 is a front right side elevational view thereof;

FIG. 9 is a rear right side elevational view thereof, the rear left side being flat and unornamented;

FIG. 10 is a top plan view thereof;

FIG. 11 is a perspective view of a third embodiment of the shelf unit shown in FIG. 1;

FIG. 12 is a front elevational view thereof;

FIG. 13 is a front right side elevational view thereof;

FIG. 14 is a rear right side elevational view thereof, the left side being flat and unornamented; and

FIG. 15 is a top plan view thereof.
